UNITED STATES PATENT OFFICE.

FREDERICK A. MELLER, OF WOONSOCKET, RHODE ISLAND, ASSIGNOR OF ONE-HALF TO FRANCIS JOSEPH O'REILLY, OF WOONSOCKET, RHODE ISLAND.

FLIER.

SPECIFICATION forming part of Letters Patent No. 694,876, dated March 4, 1902.

Application filed August 21, 1901. Serial No. 72,835. (No model.)

To all whom it may concern:

Be it known that I, FREDERICK A. MELLER, a citizen of the United States of America, residing at Woonsocket, in the county of Providence and State of Rhode Island, have invented certain new and useful Improvements in Fliers, of which the following is a specification.

This invention relates to spinning-machines, and particularly to that class known as "fliers."

The object of the invention is to produce a flier of spring-steel having the same tension as the wrought-iron forging or other fliers in common use, the said flier having a hollow arm comprising two pieces joined together in any suitable manner.

A further object of the invention is to provide a hollow flier-arm having an unusually smooth inner surface, which is a great advantage in devices of this character.

A still further object of the invention is to produce a spreader cast in a single piece and ready for use, with the exception of a single drill-hole, which is made after it is cast.

With the foregoing and other objects in view the invention consists in the details of construction and in the combination of parts to be hereinafter more fully set forth and claimed.

In describing the invention in detail reference will be had to the accompanying drawings, forming part of this specification, wherein like characters denote corresponding parts in the several views, and in which—

Figure 1 is a view in elevation of a spindle with the flier balance-arm attached. Fig. 2 is a view in elevation of a hollow arm with the elements detached. Figs. 3, 4, 5, and 6 are detail views of several elements.

In the drawings, 1 denotes the spindle, 2, a bobbin; 3, the balance-arm, and 4 the hollow arm comprising a section *a*, which is formed with the balance-arm, and a second section *b*, detachably secured to the first section. Each section of the hollow arm is provided with lugs 5, through which bolts or other like attaching means are passed. The outer edges of the section of the hollow arm are slightly separated to produce a thread-slot 6 when the sections of the arm are connected. The fixed section of the hollow arm

is provided with a shoulder 7, against which the beveled edge of the upper end of the removable section is attached.

It will be seen that a hollow arm formed in accordance with the invention when the two sections are separated may be properly finished on the inner surface to remove any roughness which would interfere with the movement of the thread therethrough. With the forged hollow arms the roughened inner surface is a matter of much annoyance at times, which is entirely obviated through the medium of the invention herein disclosed.

The footpiece or spreader 8 is cast with the socket 9 to embrace and fasten to the hollow arm through the medium of the recessed lug 10, formed on the said hollow arm. The upper end of the spreaders forming the lug is reduced in the socket, but the end 11 thereof is enlarged to form the shoulder 12, in order to prevent rotation with relation to the hollow arm. The curved portion of the spreader forming the socket 9 is sprung over the hollow arm into the recess of the lug.

The operation and advantages will, it is thought, be understood from the foregoing description, it being noted that changes in the proportions and details of construction may be resorted to for successfully carrying the invention into practice without departing from the spirit of the invention or the scope of the claims.

Having thus fully described the invention, what I claim as new, and desire to secure by Letters Patent, is—

1. The herein-described flier, having a hollow arm, comprising two sections, lugs on the hollow arms and means engaging the lugs for binding the sections together.

2. A flier comprising arms one of which is formed of separable parts, one section of the separable arm being formed with the other arm and means for securing the sections together.

In testimony whereof I affix my signature, in the presence of two witnesses, this 5th day of August, 1901.

FREDERICK A. MELLER.
